UNITED STATES PATENT OFFICE.

JOHN A. YARGER, OF NASHUA, IOWA.

VEHICLE-WHEEL.

No. 824,772.

Specification of Letters Patent.

Patented July 3, 1906.

Application filed August 21, 1905. Serial No. 275,044.

To all whom it may concern:

Be it known that I, JOHN A. YARGER, a citizen of the United States of America, residing at Nashua, in the county of Chickasaw 5 and State of Iowa, have invented certain new and useful Improvements in Vehicle-Wheels, of which the following is a specification.

This invention relates to vehicle-wheels, 10 and particularly to a wheel having a cushion action produced through the medium of a pneumatic hub and spring-held felloes.

An object of this invention is to provide a novel pneumatic hub having means for protecting the air-cell against damage through 15 the operation of the parts, and the invention further contemplates the provision of novel means for limiting the movement of the spoke-supporting rim with relation to the 20 hub.

With the foregoing and other objects in view the invention consists in the details of construction and in the arrangement and combination of parts to be hereinafter more 25 fully set forth and claimed.

In describing the invention in detail reference will be had to the accompanying drawings, forming a part of this specification, wherein like characters denote corresponding 30 parts in the several views, in which—

Figure 1 is a view in elevation illustrating a wheel embodying the invention. Fig. 2 is a transverse sectional view of the hub, showing fragments of the spokes. Fig. 3 is a sectional view on the line $x-x$ of Fig. 2.

In the drawings, A indicates the felly, which may be of any ordinary construction, provided with a series of spokes B and a series of headed studs C intermediate between 40 the spokes. The inner ends of the spokes are seated in a ring D, which ring is provided with flanges E on either side, which flanges are provided for the purpose of contacting with the hub (to be hereinafter described) to limit the movement of the ring. The hub comprises in its construction a suitable boxing F, having threaded ends to receive the nuts G, and a sectional hub H, fitted on the boxing, the said sections of the hub being internally 45 recessed to form a chamber for the reception of the inflatable bag I. The inflatable bag is circular in cross-section and has a longitudinal central tube J of such diameter as to permit the interposition of a metallic tube K between the tube J and the boxing. The 55 interposed tube K is for the purpose of pre-

venting binding of the inflatable bag on the boxing, and it permits the free rotation of the inflatable bag on the boxing, even though the bag is inflated.

A suitable tube L is in communication with the inflatable bag and extends through a section of the hub to the exterior, where a connection may be made to the source of air-supply. In order to protect the inflatable 65 bag against the action of the ring, the said inflatable bag is provided with a leather jacket or cover M, which jacket is provided with a series of metallic wear-plates N, riveted on the jackets by means of the rivets O.

In assembling the parts the inner ends of the hub-sections are separated a sufficient distance to admit the ring, and the said ring is supported in position by the cushion formed by the inflatable bag. The ring is free 70 to move within a predetermined distance, according to the yielding action of the cushion, though if the resistance of the cushion be insufficient to support the hub the flanges E will contact with the outer surfaces of the 75 hub-sections and aid in supporting the hub. It is to be observed that the wear-plates are so positioned on the jacket as to extend across the space between the hub-sections to insure the contacting of the ring with said 80 wear-plates.

As a further means for supporting the wheel and affording a yielding action I provide a series of eyes P on the hub-section and secure therein the ends of the springs Q. The 85 outer ends of the springs are provided with threaded shanks R, which are engaged by turnbuckles S, which turnbuckles are rotatable on the studs C. By means of the turnbuckles it will be observed the rim or felly 90 may be made to run true and suitable adjustment may be had for varying the tension of the springs to suit particular requirements. Through the medium of the cushion heretofore described and the springs a durable and 95 efficient yielding wheel of the cushion type is provided.

Having fully described the invention, what I claim as new, and desire to secure by Letters Patent, is—

1. In a vehicle-wheel, a hollow hub, a pneumatic cushion in the hub, a ring supported by the cushion, means for protecting the cushion, spokes carried by the ring, a felly carried by the spokes and yielding braces extending 110 from the felly to the hub.
2. In a vehicle-wheel, a suitable sectional

hub having a hollow center, a cushion seated therein, a jacket for the cushion, wear-plates on the jacket, a ring movable between the hub-sections and adapted to bear on the wear-plates, spokes carried by the ring, a felly on the spokes and yielding adjustable braces extending from the felly to the hub.

3. In a vehicle-wheel, a hollow sectional hub, means for holding the sections in operative relation to each other, a cushion in the hub, a jacket for the cushion, wear-plates for the jacket, a ring movable between the hub-sections and adapted to bear on the wear-

plates, spokes carried by the ring, a felly on the spokes, studs on the felly, springs adjustably connected to the studs and means for attaching the inner ends of the springs to the hub. 15

In testimony whereof I affix my signature, in the presence of two witnesses, this 15th 20 day of August, 1905.

JOHN A. YARGER.
